Inventor

Harley O. Heacock

By Watson E. Coleman
Attorney

UNITED STATES PATENT OFFICE.

HARLEY O. HEACOCK, OF WINSLOW, INDIANA.

BURIAL VAULT.

Application filed July 15, 1922. Serial No. 575,236.

To all whom it may concern:

Be it known that I, HARLEY O. HEACOCK, a citizen of the United States, residing at Winslow, in the county of Pike and State of Indiana, have invented certain new and useful Improvements in Burial Vaults, of which the following is a specification, reference being had to the accompanying drawings.

This invention relates to burial vaults and has for its object to provide a vault of this character in which a vacuum may be created to delay decomposition of the body in the vault.

Another object is to provide a vault of this character wherein connecting seams and like joints are eliminated to prevent leakage.

It is a further object of the invention to provide a vault of this character having a relatively large supporting member adapted to receive the edges of a cover, the cover being secured to the supporting member at spaced intervals.

With these and other objects in view, the invention consists in the improved construction and arrangement of parts to be herein-after more particularly described, fully claimed and illustrated in the accompanying drawings, in which:

Figure 1 is a perspective view of a burial vault constructed in accordance with an embodiment of the invention, portions of the cover and gasket being removed to show the interior of the vault;

Figure 2 is a transverse sectional view; and

Figure 3 is a fragmentary elevation and sectional view showing the position of the washer on the stud.

Referring to the drawings, 5 designates a flange including sides 6 and ends 7. Projecting from the upper portion of each of the sides and ends is an enlarged supporting member or flange 8, the supporting members or flanges of the sides and ends merging at the corners of the flange or receptacle, the lower surface of the supporting member inclining from the edge of said supporting member to the edge of the adjacent wall of the flange or receptacle, while the upper surface is disposed in the plane of the upper edge of the flange. By this means, a supporting member entirely surrounds the upper edge of the flange. The outer edges 9 of the flanges comprising the supporting member are extended upwardly substan-

tially at right angles to the upper face of the supporting member and in parallel relation to the sides and ends of the flange, the edges 9 cooperating substantially to provide a trough through the cooperation of the upper 60 face of the supporting member. The upper face of the supporting member is provided with a groove 10 which is disposed centrally of said upper face.

A cover 11 is provided, said cover being 65 case from metal and including a transversely curved portion which substantially forms a dome and end members 12. The edges of the cover are extended outwardly in angular relation to the dome portion of the cover 70 to provide a flange 13, said flange having spaced openings 14 centrally thereof. The trough formed by the cooperation of the edges 9 of the supporting member is intended to receive the flange 13 of the cover. 75 Projecting from the upper face of the supporting member inwardly of the groove 10 is a plurality of spaced threaded studs 15 adapted to extend through the openings 14 in the cover. To insure the air tight connection of the cover to the vault, a gasket 16 is provided, said gasket being made preferably of lead and formed from a single sheet of material. This gasket includes an inner flange 17, a curved portion 18 and an 80 outer flange 19. The outer flange 19 is intended to engage the inner face of the edge 9 of the supporting member, while the curved portion 18 is intended to enter the recess 10, the flange 17 being provided with 85 openings for the reception of threaded studs carried by the supporting member. By this means when the cover is placed on the vault the gasket will be urged into binding engagement with the supporting member and 90 the cover and compressed by nuts carried by the studs so as to render the vault air tight.

In order that there may be no possibility of leakage, washers 20 are provided, each 100 washer having a compressible collar 21 at its inner edge. The collar is urged around the threads of the bolt when the washer is compressed by the nuts of the bolts. To exclude the air that may be within the vault, 105 after the body has been deposited and the cover applied, the cover is provided with a valve 22, the port 23 being interiorly threaded for the reception of a pump, by means of which the air may be pumped from the vault. 110

In order to test the vault, the valve may be operated so as to permit air to be pumped in the vault and then a test made to see that no portion of the vault leaks. The pump 5 is then reversed so as to remove the air from the vault, whereupon the valve 22 may be closed, thereby producing a vacuum within the vault which delays or prevents decomposition to a large extent, and maintaining 10 the body in its natural state indefinitely.

What is claimed is:—

A burial vault comprising a receptacle having an endless enlarged end portion at its upper edge adapted to form a supporting member, a flange extending upwardly from the outer edge portion of the upper face of the supporting member, said upper face of the supporting member having a longitudinally extending groove disposed in 15 spaced relation to the flange and the inner edge of the supporting member; an endless 20

compressible gasket engaged with the upper face of the supporting member, the outer edge of said gasket being extended upwardly at right angles to the major portion of the 25 gasket to provide a flange, and engaged with the inner face of the flange of the supporting member, that portion of the gasket disposed between the flange thereof and the inner edge portion of the gasket being substantially crimped longitudinally of the gasket and extended into the groove of the supporting member, and a cover having an endless rib depending from the lower face thereof and arranged to enter said crimp and firmly engage the gasket, the outer edges of 30 the cover being adapted to firmly engage the inner face of the flange of the gasket.

In testimony whereof I hereunto affix my signature.

HARLEY O. HEACOCK.
